LIFE PRESERVER LIGHT

Henry M. Slocum, New York, N. Y., assignor to
 Colvin-Slocum Boats, Inc., New York, N. Y., a
 corporation of New Jersey

Application August 27, 1942, Serial No. 456,392

4 Claims. (Cl. 240—10.68)

The present invention relates to new and improved constructions in portable, self-contained illuminating devices, commonly referred to as flashlights. Although not confined to such use, the light of the present invention has been designed especially for use with life preservers on ships at sea, or for use with life rafts, collapsible boats or the like, carried by aircraft, or surface or submersible vessels.

A primary object of the invention is to provide a flashlight which will not be adversely affected by long exposure to salt water or sea air. The invention aims to provide a light which will never fail to operate, even under the most adverse conditions and after long periods of non-use. To this end the invention provides a flashlight of extreme simplicity of design, having no exposed metal parts and having all of the electrical connections and contact elements substantially hermetically sealed in a noncorrosive casing.

Thus, an important object of the invention is to greatly simplify the construction of flashlights, to reduce the number of parts thereof, and to simplify their assembly into complete units.

A further object of the invention is to provide a flashlight constructed substantially entirely of molded plastic materials.

Another object of the invention is to provide a flashlight wherein the internal, metallic parts are substantially hermetically sealed, so that water and external gases, such as sea air, can not gain access thereto and exercise a corrosive effect thereon.

A further object of the invention is to provide an improved, simplified electric switch construction for controlling the bulb circuit, characterized by the absence of switch buttons or other elements extending through the casing.

A further object is to provide a novel closure member for a flashlight, adapted to function as a closure, as a lens element, and as a switch operating member for controlling the bulb circuit.

Other and further objects and advantages of the present invention will be apparent to those skilled in the art, from a consideration of the following description of a specific embodiment of the invention, shown in the accompanying drawings, in which:

Fig. 1 is a side elevation;

Fig. 2 is a longitudinal section;

Fig. 3 is a transverse section on line 3—3 of Fig. 2;

Fig. 4 is a fragmentary detail showing certain parts in one position;

Fig. 5 is a similar view showing the parts in another position; and

Fig. 6 is an exploded sectional view.

As mentioned above, the invention of the present application is particularly adapted for use with life preservers, life rafts, or other life-saving devices, the primary object being to enable a person in distress in the water to signal airplanes or surface vessels searching for him. It is contemplated that a light will be attached to each life preserver on a ship, and one or more lights similarly attached to collapsible life rafts or boats in airplanes. To this end, a cord 10 is looped through an aperture 11 in a lug 12 projecting rearwardly from the end 13 of the cylindrical case 14. At its other end the cord 10 is securely attached to a safety pin 15 or other securing device, preferably constructed of non-corrosive metal such as brass.

The case 14 also is provided with a second lug 16 having an aperture 17 therein through which a link 18 is looped, for the attachment of a clamp 19, of the type used for storage battery connectors or the like. The safety pin 15 may be secured to the life preserver or the like and the clamp 19 attached, when in use, to some convenient part of the wearer's apparel. Thus, by releasing the clamp 19 the person in distress may handle the flashlight, for instance, for signaling purposes, without any danger of losing it. The cord 10 provides a permanent connection to the life preserver while still afford freedom of manipulation of the light.

As pointed out above, the light of the present invention is preferably constructed of molded plastic materials. The case 14 may be made from any suitable plastic material, such as synthetic resin, Bakelite, Celluloid, cellulose acetate or any of the other standard plastics of commerce. The case includes a substantially cylindrical side wall 25 having outwardly projecting ribs or flutes 26, a closed rear end 13 and an open end 27. Adjacent to but spaced from the open end there is an outwardly projecting threaded section 28, leaving an annular recess 29 beyond the thread for the reception of a sealing gasket 30 as hereinafter explained.

At the forward open end of the case there is a combined closure and lens member 32, comprising an internally threaded sleeve or collar 33 and a dome shaped end member 34 connected 55 marginally to the collar by an integral, annular

shoulder 35. This member is preferably made from a transparent or translucent plastic, suitably colored if desired, for instance, to produce a red beam of light. The exterior surface 36 of the dome shaped end member is preferably substantially semi-spherical, while the marginal portion 36' of the inner surface thereof is concentric therewith. The central portion of the inner surface, however, is substantially plane, as indicated at 37, thereby providing a lens 38 at the end of the closure, between the plane inner surface and the curved outer surface.

The gasket 30 of rubber or other compressible, water and gas resistant material, may be compressed between the bottom of the annular recess 29 and the inner surface of the collar 33, the latter being non-threaded at this portion. The gasket provides a substantially hermetic seal between the cap 32 and the case 14. In many cases the gasket may be omitted as the relatively long, tight fitting threaded connection between the cap and the case provides a satisfactory seal.

At one point in the outer circumference of the open end of the case, there is provided a recess 40 for the reception of the hooked end 41 of a strip 42 of spring metal, such as phosphor-bronze, having its major portion lying along the inner side wall of the case and its rear end 43 projecting radially inwardly and bent forwardly as at 43', to provide a spring seat for the battery 44 disposed within the case. It will be apparent that the strip 42, with its forward end hooked over the end of the case and with its rear end behind the battery, urges the battery forwardly, when the rear end is placed under stress, as herein-after explained. Moreover, the strip is in electrical connection with the bottom end or negative terminal of the battery and will, therefore, be negatively charged.

In the space between the annular shoulder 35 and the open end of the case there is positioned a circular plate 45 having a centrally positioned bulb socket 46 carried thereby. A bulb 47 is threaded in the socket and preferably retained therein by a locking spring 48. These parts are of such size and are so proportioned that the margin of plate 45 is engaged by shoulder 35 and the central terminal 49 of the bulb 47 is in contact with the positive pole 50 of the battery, urging the battery rearwardly against the stress of the spring end 43' of the strip 42. In other words, when the parts are in the normal position, the spring 43' is stressed, thereby urging the battery forwardly and, through bulb 47, urging the plate 45 into contact with the shoulder 35, so that the margin of the plate is spaced outwardly from the hooked end 41 of the strip 42, out of electrical contact therewith.

In order to complete the bulb circuit and energize the light 47, it is simply necessary to screw the closure member 32 and the collar 33 rearwardly upon the case. The shoulder 35 forces the plate 45 rearwardly until the margin thereof makes contact with the hooked end 41 of the strip 42. Hence, the circuit is completed from the positive terminal 50 of the battery through the central terminal 49 of the bulb, the bulb filament, the bulb sleeve, the socket 46, the plate 45, and the strip 42, back to the bottom end or negative terminal of the battery.

In order to facilitate screwing the cap 32 on the case, the collar 33 is provided with a plurality of outwardly projecting flutes 55. In addition, an externally projecting lug 56 may be molded integrally with the lens and collar, in order to

provide a positive abutment for the thumb of the user and to prevent slippage.

The extreme simplicity and fool-proof character of the light of the present invention will be apparent from the foregoing description. The construction includes only four essential parts, in addition to the standard bulb and battery. There are (a) the case 14, (b) the closure 32, (c) the socket-carrying plate 45, and (d) the strip 42 of spring metal. Each of these four parts is separate and independent of the others and may be manufactured separately. The assembly of the parts into cooperative relationship to form a complete flashlight is an extremely simple operation. The spring strip 42 is inserted in the case with the hooked end 41 in the recess 40, and the battery is dropped into place. The bulb is screwed into the socket, and the plate 45 placed in the cap 32. The cap and case are screwed together and the assembly is finished. When it is desired to illuminate the light, the cap 32 is simply screwed tightly upon the case, thereby completing the bulb circuit, as previously explained. Obviously the light may be extinguished by simply unscrewing the cap slightly to permit the plate 45 to move away from the hooked end 41 of the strip 42, under the influence of the force of the spring provided at the end 43 of the strip, acting through the battery and the bulb.

The independent, separate, unitary strip spring element 42 is an important feature of the present invention, since it, in combination with the socketed plate 45, contributes to the simplicity of the construction and the ease of assembly of the parts. It is substantial improvement over construction where electrical conducting strips are moulded into flashlight cases or attached thereto by rivets or the like.

It is thought that the construction, operation and advantages of the embodiment of the present invention shown in the accompanying drawings will be entirely clear from the foregoing description. It must be understood, however, that the invention is not limited to the details of construction shown in the drawings and described above, since all modifications coming within the scope of the appended claims and their equivalents are included.

I claim:

50. 1. A substantially air tight and waterproof flashlight adapted for use by a person stranded at sea, comprising a cylindrical case having an open end and a closed end, a strip of spring metal lying along the wall of the case and having one end hooked over the open end of the case in tight engagement therewith and the other end projecting inwardly from the side wall and spaced from the closed end and constituting a spring seat for a battery, a battery supported by said spring seat and urged outwardly toward the open end of the case, a one piece molded cap having an imperforate substantially transparent face and an integral outwardly projecting collar threaded upon the open end of the case in substantially air and watertight relation, said collar being joined to the lens by a shoulder, a socketed plate disposed within the collar of the cap and having its margins normally spaced outwardly from the hooked end of the strip, and a bulb 60 in the socket enclosed by said cap and having its central terminal continuously contacted by the central terminal of the battery as the same is urged outwardly by said spring seat, the outward movement of the battery and the bulb being limited by the engagement of the socketed
- 65
- 70
- 75

plate against said shoulder, whereby the plate may be brought into contact with the hooked end of the strip to complete the bulb circuit by screwing the collar upon the case.

2. A substantially air tight and waterproof flashlight of the type adapted for use by a person stranded at sea, comprising a tubular case having a closed rear end and an open forward end, a flexible line of substantial length attached adjacent the closed end of the case and having means at its free end for attachment to a life preserver, clamping means permanently attached to the tubular side wall of the case for clamping the flashlight to the clothing of the person stranded at sea, a combined closure and lens for the case comprising a collar snugly threaded on the open end of the case in substantially air and water tight relation and having an inwardly projecting annular shoulder adjacent its forward end and integral with the closure, a circular plate mounted within the collar and having a central bulb socket, a bulb in the socket projecting into the closure, a battery in the case, and a single strip of flat spring metal lying along the inner surface of the case and attached thereto with its forward end exposed at the open end of the case and its rear end bent inwardly in outwardly spaced relation to the closed end thereof and acting as a spring seat for urging the battery outwardly and continuously into contact with the bulb and for urging the plate outwardly and continuously against the annular shoulder and normally in spaced relation from the forward end of the strip, whereby said plate may be moved into contact with the forward end of the strip by screwing the collar inwardly upon the case to complete the bulb circuit.

3. A flashlight comprising a molded, plastic cylindrical case closed at its rear end and having an externally screw-threaded open forward end, a transparent one-piece cap comprising an internally threaded collar tightly screwed upon the

threads of the case, an imperforate dome shaped lens of less diameter than the collar projecting outwardly from the forward end thereof and joined thereto by a shoulder projecting inwardly from the collar, a flat circular plate having a centrally positioned bulb socket disposed in said cap with the margins of the plate adjacent said shoulder, a bulb in said socket, a strip of spring metal lying along the inner surface of the side wall and the bottom of the case and having its forward end hooked over the open end of the case and its rear end bent upwardly from the bottom, and a battery having its base supported upon the rear end of the strip and its end terminal in contact with said bulb, the rear end of said spring strip acting through the battery and the bulb, serving to urge the plate forwardly against the shoulder in the cap and out of contact with the forward end of the strip, the margin of the plate being movable into contact with the forward end of the strip to complete the bulb circuit by screwing the collar upon the case.

4. A flashlight comprising a case having a cylindrical side wall, a closed rear end and an exteriorly threaded open forward end and a lug projecting laterally from the side wall, a combined closure and lens element for the case comprising an externally fluted collar threaded on the open end of the case, a substantially semi-spherical, dome shaped member integrally joined thereto by a circular intermediate shoulder and a lug integral with the lens and projecting laterally therefrom and extending substantially from the center of the lens to the circumference of the collar, a battery in the case, a bulb and socket in the closure element, means for urging the battery outwardly into contact with the bulb and means for completing the bulb circuit when the closure element is screwed down upon the case, said lugs on the case and closure serving to provide finger grip abutments to facilitate such action.

HENRY M. SLOCUM.
